UNITED STATES PATENT OFFICE

2,452,803

SELF-ADJUSTABLE SHOE UPPER

Esther Sudiah, Brooklyn, N. Y., and Rachel Sudiah, deceased, late of Brooklyn, N. Y., by Esther Sudiah, legal representative, Brooklyn, N. Y.

Application November 20, 1946, Serial No. 711,186

1 Claim. (Cl. 36—12)

1

This invention relates to an improved shoe, and one of its objects is to provide a shoe with an upper which will expand to prevent excessive pressure on a foot which has swelled from exercise or any physiological cause.

Another object of the invention is to provide a shoe with an upper which may be detached by the wearer himself from the sole and heel, and a different upper connected thereto, without requiring special skill, so that warmer or cooler uppers may be used in winter or summer, as the wearer may desire.

With the above and other objects in view the invention comprises certain new and useful constructions, combinations and arrangements of parts, clearly described in the following specification, and fully illustrated in the drawings, in which:

Fig. 1 is a perspective of a completed shoe.

Fig. 2 is an assembly view in perspective of three complementary parts for binding the out-turned edge of the upper to the marginal edge of the sole.

Fig. 3 is a transverse sectional view, taken on line 3—3 of Fig. 1, looking in the direction of the arrows.

Referring to the drawings, which illustrate the practical embodiment of the invention, 5 designates a shoe upper, which may be constructed of any suitable material, leather, fabric, or composition material, and which is formed with an outturned marginal edge 6.

The marginal edge 6 is secured to the marginal edge 7 of the sole 8, which may be leather or any other material, by means of the clamping unit 9, which consists of a U-shaped forward section 10, opposing side sections 11 and 12, and a U-shaped rear section 13.

The forward section 10 is formed with an inner U-shaped jaw 10a and an outer U-shaped jaw 10b, which is connected thereto by the hinge 10c, which is equipped with a spring closing coil 10d, adapted to hold the inner jaw 10a in clamping relation to the outer jaw 10b.

The side section 11 is constructed with an inner or upper jaw 11a and a lower or outer jaw 11b, connected to each other by the edge spring 11c and the hinges 11d. The side section 12 is constructed with a lower or outer jaw 12a and an upper jaw 12b, which are connected to each other

2

by means of the hinge 12c and held toward each other by means of the coil spring 12d.

The U-shaped rear section 13 is constructed with an upper jaw 13a which is hinged to the lower or outer jaw 13b by means of the hinge 13c, and engaged by the coil spring 13d.

The inner section of each part of the clamping unit is adapted to swing upwardly, and the lower or outer section is secured to the marginal edge 10 of the sole 8 by means of the tacks 14.

The outer edge of the sole 8 is faced by an edging strip or loop 15, and the upper leaf of each section of the clamping unit is faced by a striping 16. This striping is constructed in sections corresponding to the shape and size of the sections of the clamping unit, but provided with adjacent overlapping ends. The section 16a is adapted to cover the forward unit section 10, the section 16b is adapted to cover the unit section 11, the section 16c is adapted to cover the side unit section 12, and the section 16d is adapted to cover the unit section 13. The adjacent ends of the sections overlap at 17, 18, 19 and 20, and are coupled to each other by means of the button snaps 21.

The marginal edge of the flexible upper 5 is held to the sole solely by the clamping action of the unit 9, and when unusual pressure is applied to the upper, the upper may expand by slipping its connection with the sole, thus avoiding extreme pressure on the foot, preventing the development of corns, and providing means for maintaining the shoe in the most desirable service condition.

At various times of the year the feet have a tendency to expand or spread out, and because of a large variety of physiological causes feet will swell. It is found that persons subject to expansion of their feet will suffer keenly, and the present invention provides means for relieving pressure on the feet to prevent pain and general discomfort.

By opening the upper leaves of the sections of the clamping unit the upper may be entirely detached, and a different upper connected with the shoe sole, the rear end of which is provided with the usual heel 8a, permanently connected to the sole.

It is understood that various changes in the details of construction, their combination and ar-

angement of parts, may be made, within the scope of the claim which defines the invention.

Having described the invention, it is claimed:

A shoe having a sole and an upper having a turned marginal edge disposed on the sole, and a clamping unit consisting of individual sections hinged to the sole and adapted to clamp the marginal edge of the upper thereto.

ESTHER SUDIAH. 10
ESTHER SUDIAH,
